ALKYLATION WITH GASEOUS OLEFINIC MATERIAL

Filed March 3, 1942

UNITED STATES PATENT OFFICE

2,384,736

ALKYLATION WITH GASEOUS OLEFINIC MATERIAL

Frederick E. Frey, Bartlesville, Okla., assignor to
Phillips Petroleum Company, a corporation of
Delaware

Application March 3, 1942, Serial No. 433,204

5 Claims. (Cl. 260—683.4)

This invention relates to the conversion, by an alkylation reaction in the presence of a liquid catalyst, of relatively low-boiling hydrocarbons to higher-boiling hydrocarbons. More particularly, it relates to the efficient utilization of a comparatively inert gaseous hydrocarbon stream containing a relatively small proportion of olefins as a source of olefins for use as the alkylating agent.

Prior to this invention, the feeds to practical hydrofluoric acid alkylation processes have comprised relatively large proportions of reactive ingredients; for example, the feed used for the alkylation of isobutene with butylenes ordinarily contains a total of fifty per cent or more of isobutane plus butylenes. Heretofore, a feed having a relatively high proportion of inert diluent material has required equipment of excessive size. Furthermore, prior to this invention, the feeds to practical hydrofluoric acid alkylation processes have been liquid-phase. Gaseous feeds have been used for non-catalytic or thermal alkylation, which has the disadvantage that relatively high pressures are required.

The object of my invention is to provide a relatively simple, low-cost hydrocarbon-conversion process wherein a relatively inert gaseous stream containing comparatively small proportions of olefin hydrocarbons may be utilized efficiently as a source of alkylating agent for converting relatively low-boiling hydrocarbons to higher-boiling hydrocarbons.

A further object of my invention is to eliminate large volumes of unreactive material from an alkylation process in an early step, thereby increasing the capacity of the equipment.

Further objects and advantages of my invention will be apparent from the following description and the accompanying drawing.

Olefin hydrocarbons are very soluble in concentrated or anhydrous hydrofluoric acid, and polymerization of olefins in concentrated hydrofluoric acid occurs rapidly at atmospheric temperatures. Consequently, in the prior art of catalytic alkylation of hydrocarbons, there is a theory that the olefins must not come in contact with hydrogen fluoride except in low concentrations of olefins and in the presence of a large excess of alkylatable material; that is, the olefins or other alkylating agents have usually been added slowly with rapid agitation to a mixture comprising hydrogen fluoride and an alkylatable hydrocarbon under alkylation conditions. I have found that, in a process for alkyllating saturated hydrocarbons with olefin hydrocarbons in the presence of concentrated or anhydrous hydrofluoric

acid, the olefins can be advantageously absorbed, under certain specific conditions which will be described hereinafter, by hydrofluoric acid prior to contacting, under alkyllating conditions, with 5 an alkylatable hydrocarbon; the resulting acid solution, when used as an alkylating agent, produces in high yield a product of high octane number suitable for use in aviation motor fuel. I have found that objectionable polymerization 10 of the olefins absorbed in hydrofluoric acid is averted effectively by controlling the acid-to-olefin ratio, the temperature, the acid concentration, and the period of residence of the olefin in the acid prior to mixing with an alkylatable hydrocarbon under alkyllating conditions. I have found also that polymerization is controllable to some extent by adding small proportions of water, for instance, 5 to 35 per cent, to the absorbing acid. Further, I have found that, by applying the above-mentioned discoveries to hydrofluoric acid alkylation processes, gaseous hydrocarbon streams comprising olefins in proportions of from 5 per cent or less to 50 per cent or more may be utilized advantageously as a source of 15 alkylating agent in a process for the conversion of relatively low-boiling hydrocarbons to high-boiling hydrocarbons.

Understanding of some aspects of my invention may be aided by the accompanying drawing, 20 which is a schematic flow-diagram of one arrangement for practicing the invention.

A gaseous olefin-containing hydrocarbon material is admitted through inlet 11, valve 12, and distributing means 13 near the bottom of gas-phase absorber 14. In the lower section of absorber 14, which preferably is packed, the gas is passed upwardly and is contacted intimately and countercurrently with downwardly flowing concentrated hydrofluoric acid, which absorbs olefins from the gas, and which may be admitted through inlet 15, valve 16, and distributing means 17 in the central part of absorber 14. In the upper section of absorber 14, which also preferably is packed, the gas is also passed upwardly 25 and is contacted intimately and countercurrently with a downwardly flowing relatively dilute aqueous solution (preferably a constant-boiling mixture) of hydrofluoric acid, which absorbs vaporous hydrogen fluoride from the gas, and which may be admitted through inlet 18, valve 19, and distributing means 20 near the top of absorber 14. Additional details relating to the absorptions occurring in absorber 14 are given hereinafter.

The olefin-depleted gas is passed from the top 30 of absorber 14, through conduit 21 and valve 22,

to washer 23, wherein it is contacted with substantially pure water, which is admitted through conduit 24, having valve 25, and which absorbs any remaining small proportions of hydrogen fluoride. The olefin-depleted, hydrogen fluoride-free gas is withdrawn through outlet 26 having valve 27.

The olefin-in-acid phase is passed from the bottom of absorber 14, through conduit 28 and valve 29, to alkylator 30, wherein, under alkylating conditions, such as 30 to 150° F., a pressure sufficient to maintain all components in the liquid phase, and for a time of about one to thirty or more minutes, it is agitated with an alkylatable hydrocarbon, such as isobutane or isopentane, which may be admitted through inlet 31 and valve 32. To increase the amount or the strength of the catalyst, additional concentrated or anhydrous hydrofluoric acid may be advantageously admitted to the alkylator, as through conduit 33 and valve 34 and/or valve 35.

The resulting mixture passes as the effluent from alkylator 30, through conduit 36 having valve 37, to separator 38, wherein it is separated, by gravitational or centrifugal means, into two liquid phases.

Of these phases, the lighter or hydrocarbon phase is passed through conduit 39 having valve 40 to fractionator 41, by which it is separated into the following six fractions: (1) a very minor fraction, comprising non-condensable gases, which is withdrawn through outlet 42 having valve 43; (2) a minor fraction comprising an azeotropic mixture of hydrogen fluoride and relatively low-boiling hydrocarbons, such as propane and butane, which passes via valve 44 and conduit 45 to separator 46; (3) a comparatively large fraction comprising unreacted readily alkylatable hydrocarbons, such as isobutane or isopentane, which is recycled via conduit 47, pump 48, and valve 49 to alkylator 30; (4) a fraction comprising relatively difficultly alkylatable hydrocarbons, such as normal butane, which is removed through outlet 50 having valve 51; (5) a substantial fraction of the desired highly-branched paraffinic reaction products boiling within the gasoline range, which is withdrawn through outlet 52 having valve 53; and (6) a high-boiling bottom fraction or oil, comprising polymers and other byproducts, which is withdrawn through outlet 54 having valve 55.

The heavier or hydrofluoric acid phase from separator 38 is recycled to absorber 14 and/or alkylator 30 by way of conduit 56 and valve 57 and/or valve 85, respectively. Preferably, however, a part of it is passed through conduit 58 and valve 59 to acid-fractionation unit 60, wherein it is separated into the following three fractions (1) a major fraction, comprising substantially anhydrous hydrogen fluoride, which is recycled via conduit 61, pump 62, and valve 63 and/or valve 35 to olefin absorber 14 and/or alkylator 30, respectively; (2) a fraction, comprising a constant-boiling or maximum-boiling mixture of water and hydrogen fluoride which is passed partly via conduit 64 and valve 65 to the top section of absorber 14, for use as absorbing liquid as already described, and partly via conduit 66 and valve 67 to low-pressure fractionator 68; and (3) a bottom fraction, comprising hydrocarbon residue and high-boiling by-products, which is withdrawn through outlet 69 having valve 70.

In separator 46, by cooling and gravitational

or centrifugal means, the aforementioned azeotropic mixture from fractionator 41 is separated into two liquid phases. The lighter or hydrocarbon phase is withdrawn through outlet 71 having valve 72, and the heavier or hydrofluoric acid phase is passed through conduit 73 and valve 74 to fractionator 60.

Fractionator 68, operated at a pressure lower than in fractionator 60, separates the constant-boiling mixture from fractionator 60 into two fractions: (1) a minor fraction of substantially pure water, most of which is recycled via conduit 75, pump 76, and valve 25 to washer 23, but a part of which may be withdrawn through outlet 78 having valve 79, to compensate for excess water entering the system with the various feeds or otherwise, and a part of which, if desired, may be recycled to absorber 14 through valve 77; and (2) a major fraction, comprising a constant-boiling or maximum-boiling mixture of hydrogen fluoride and water, which, because of the effect of a decrease in pressure upon the composition of a constant-boiling mixture, is relatively richer in hydrogen fluoride than the constant-boiling mixture from fractionator 60, and which is recycled via conduit 80, pump 81, and valve 82 to fractionator 60. The pressure in fractionator 68 is preferably of the order of one atmosphere or less, whereas that in fractionator 60 is preferably several atmospheres or more.

A dilute aqueous solution of hydrogen fluoride is withdrawn from washer 23 and is passed through valve 83 and conduit 84 to fractionator 68. If desired, this solution may be passed to an intermediate fractionator, not shown in the drawing, to be separated into two fractions, (1) water and (2) a constant-boiling mixture, only the latter of which would be passed to fractionator 68.

The olefin-containing feed to my process may be any normally gaseous hydrocarbon material which boils appreciably below hydrogen fluoride. It preferably contains olefins heavier than ethylene, such as propylene, butylenes, or amylenes. Preferably the proportion of total olefins is in the range from about 5 to about 50 per cent by volume of the feed. Feed material containing proportions of olefins smaller than 5 per cent requires handling excessive volumes of diluent material; feed material containing proportions of olefins larger than 50 per cent may usually be admitted directly to the alkylation unit. Fractions containing propane and lighter, including 5 per cent or more propylene are especially suitable for use as feed to my process.

Many modifications of the absorbing system are possible, such as, for example, a series of washers in which the olefin-containing feed material is contacted in succession with concentrated hydrofluoric acid, one or more aqueous acid solutions in the order of decreasing concentration, and finally pure water. The one or more concentrated acid extracts, which contain dissolved olefins, may be passed to the alkylator; the one or more dilute acid extracts, which are substantially pure aqueous solutions of hydrogen fluoride, may be passed to an acid-recovery unit, or an acid effluent from one washer may be used as the absorbing liquid in an absorber using a more concentrated solution of acid. In another modification, a centrifugal-type contactor may be used to contact the gaseous olefin-containing material with concentrated hydrofluoric acid, whereby the olefins are absorbed by the acid; the olefin-depleted gas from the centrifugal-type contactor may then be washed with dilute aqueous

hydrofluoric acid and/or water to recover vaporous hydrogen fluoride.

In general, the absorption system has the following three functions: (1) to transfer olefins from a gas phase to a liquid hydrofluoric acid phase in a short time without objectionable polymerization; (2) to wash out and recover organically combined fluorine from the olefin-depleted gas; and (3) to wash out and recover hydrogen fluoride vapors from the olefin-depleted gas. The manner in which the absorption system embodied in the accompanying drawing accomplishes these functions may be visualized as follows: In absorber 14, in a short space immediately above gas-distributing means 13, the olefins are absorbed by liquid concentrated hydrogen fluoride, of which an appreciable amount is vaporized. Some alkyl fluorides formed by the addition of hydrogen fluoride to olefins are also present in the vapor phase. In the zone next above this and below distributing means 17, fresh countercurrently-flowing liquid concentrated hydrofluoric acid absorbs the vaporous alkyl fluorides. In the upper section of absorber 14, dilute aqueous countercurrently flowing hydrofluoric acid extracts most of the hydrogen fluoride vapor, and in washer 23, water extracts substantially all the remaining hydrogen fluoride.

The quantity of water used in washer 23 is preferably about 1 to 10 per cent by weight of the olefin-depleted gas. The optimum proportion, of course, depends upon the concentration of hydrogen fluoride in the effluent gas from absorber 14. The aqueous hydrogen fluoride introduced through distributing means 20 near the top of absorber 14 is preferably a maximum-boiling solution; the amount is preferably about 5 to 20 per cent by weight of the hydrocarbon gas being treated. Using smaller proportions does not remove the vaporous hydrogen fluoride sufficiently completely, and consequently overloads washer 23, whereas using larger proportions introduces so much water as to affect adversely the subsequent alkylation step. The quantity of concentrated hydrofluoric acid introduced through distribution means 17 at the middle of the absorber preferably is from about one-fourth to about four times the weight of hydrocarbon treated and should be at least five times the weight of aqueous solution introduced at the top of the absorber. Smaller proportions are likely to cause excessive polymerization of olefins or else to be excessively diluted by the aqueous solution introduced at the top of the absorber, whereas larger proportions may produce unnecessarily high acid-to-hydrocarbon ratios subsequently in the alkylator. In general, the optimum proportions and concentrations of the various solutions will depend somewhat upon the particular hydrocarbons used, the operating conditions, and the design of the equipment, but suitable proportions may be readily determined by trial.

Preferably, the absorption system is fitted with a cooling means to extract the heat of absorption of olefins in the hydrogen fluoride. The vapor pressure of hydrogen fluoride increases rapidly with increase in temperature above room temperature. Thus the load on the hydrogen fluoride recovery part of the absorption system is decreased by the use of low temperatures. Also, as has been pointed out already, the extent of undesirable side reactions is reduced by lowering the temperature of the olefin-in-acid phase. A suitable cooling means, for example, consists of one

or more cold-water coils situated within the absorber and/or the acid washers.

I have found that the rate of polymerization of olefins in hydrofluoric acid is reduced considerably if some water is present in the acid. However, although alkylation with hydrofluoric acid containing up to about ten per cent water produces in high yield a product of good quality, both the quality and the yield may be somewhat inferior to those obtained by alkylation with acid containing less water. Therefore, it is advantageous to have a higher concentration of water present in the acid phase of the olefin-extraction step than in the acid phase of the alkylation step. This desirable end can be attained in a modification of my process in which the combined hydrofluoric acid phases introduced to the olefin-extraction step have a relatively lower concentration, such as 65 to 90 per cent by weight, the balance being water, and in which a proportion of substantially anhydrous hydrofluoric acid large enough to raise the average concentration to the desired value, at least 90 per cent and preferably higher, is introduced in the alkylation step. This modification of my invention is advantageous in instances in which unusually large tendencies to polymerization are encountered. Usually, however, in order to simplify the operation and to maintain a high acid-to-olefin ratio in the absorption operation, it is preferable to introduce all the hydrogen fluoride, in concentration sufficient to obtain efficient operation of the alkylation step, into the absorption step, and to depend upon control of time, temperature, and acid-to-olefin ratio to avert undesirable polymerization reactions.

The preferred time interval for passing the olefins through the absorption system to the inlet of the alkylator is in the range 5 to 60 seconds; the preferred temperature is in the range 30 to 150° F.; and the preferred ratio of hydrofluoric acid to olefin is in the range 10:1 to 20:1 by weight. These variables are mutually interdependent; for example, at the lower temperature and the lower acid-to-olefin ratio or longer time interval, approximately the same results are obtained as at higher temperature and a higher acid-to-olefin ratio or a shorter time interval. Good results can be obtained outside the ranges given, but these ranges are preferred for practical reasons as follows: The preferred time intervals are easily obtainable with absorption or extraction equipment of conventional design; the preferred temperatures are near atmospheric and are therefore obtainable with little or no refrigeration; the preferred acid-to-olefin ratios are suitable for operation of the alkylation step. The pressure in the absorption system should be sufficient to maintain a liquid hydrogen fluoride phase, and preferably in the range 40 to 200 pounds per square inch. The exact optimum conditions for any particular case may be readily determined by trial.

In some cases, the step of recovering hydrogen fluoride from the maximum-boiling mixture may be optional. The separation is difficult even by the method embodied within the flow-diagram of the accompanying drawing, of distilling alternately at different pressures. If this step is not practiced, advantage may be taken of the fact that aqueous solutions of hydrogen fluoride have a commercial value and can be disposed of for other uses than alkylation. In any case, the operating conditions of my process may be so controlled that only a relatively small proportion of

by-product maximum boiling aqueous solution is produced.

To illustrate some of the many aspects of my invention, the following specific examples are given:

Example I

A depropanizer overhead fraction comprising 13.5 per cent propylene by weight is fed to a system of the type already described. In the absorption step, the average temperature is 53° F.; the pressure is 95 pounds per square inch; the average time of residence of the propylene in the extractor and the conduit leading to the alkylator is about 20 seconds; a proportion of maximum-boiling aqueous hydrogen fluoride equivalent to 10.4 per cent by weight of the total olefinic feed is introduced at the top of the absorber, and a proportion of substantially anhydrous hydrofluoric acid equivalent to 220 per cent by weight of the total olefin feed is introduced at the middle of the absorber. The average effective concentration of the hydrofluoric acid is about 95 per cent, the other 5 per cent being water. The acid-to-olefin ratio in the effluent from the absorber is about 17.1 by weight. In the alkylator, the conditions are: temperature, 66° F.; average time of residence, 14 minutes; pressure, 45 pounds per square inch; rapid agitation with isobutane, which is introduced into the alkylator at a rate of about 7 moles per mole of olefin introduced. The alkylator effluent is separated by gravity into an acid phase and a hydrocarbon phase. About half of the acid phase is recycled to the middle of the absorber for use as absorbing liquid and the other half is passed to an acid recovery system of the type already described in connection with the accompanying drawing. The hydrocarbon phase is subjected to debutanization, from which an isobutane fraction is recycled to the alkylator. The normally liquid debutanized alkylate is characterized as follows:

Yield, wt. per cent of olefin	209
Olefin content	0.6
Composition, vol. per cent:	
$<C_8$ (<95° C.)	76.1
C_8 (95-125° C.)	19.9
$>C_8$ (>125° C.)	4.0

An aviation-gasoline cut is obtained from this alkylate in a yield of 99 per cent by volume; it has an ASTM octane number of 90.7, which is increased to 100.4 by the addition of 1 cc. of tetraethyl lead per gallon.

Example II

A refinery gas containing 9.3 per cent by weight butylenes, 6.7 per cent by weight propylene, some normal butane, some propane, and a substantial proportion of ethane, methane, and hydrogen is subjected to the process of Example I under the following conditions: Average absorber temperature, 75° F.; absorber pressure, 125 pounds per square inch; average time of residence of the olefins in extractor and conduit leading to the alkylator, about 30 seconds; a proportion of maximum-boiling aqueous hydrogen fluoride, introduced at the top of the absorber, equivalent to 8.5 per cent by weight of the total olefinic feed; and a proportion of substantially anhydrous hydrofluoric acid, introduced at the middle of the absorber, equivalent to 180 per cent by weight of the total olefinic feed. The average effective concentration of the hydrofluoric acid is about 95 per cent. The acid-to-olefin ratio in the absorber effluent is about 11.2 by weight. In the alkylator

the conditions are: temperature 97-104° F.; average reaction time, 4.75 minutes; pressure 115 pounds per square inch; rapid agitation with isobutane which is introduced into the alkylator at a rate of about 11.5 moles per mole of olefin introduced. The alkylator effluent is separated by gravity into an acid phase and a hydrocarbon phase. About half of the acid phase is recycled to the middle of the absorber for use as absorbing liquid, and the other half is passed to an acid-recovery system of the type already described in connection with the accompanying drawing. The hydrocarbon phase is subjected to debutanization, from which an isobutane fraction is recycled to the alkylator. The normally liquid debutanized alkylate is characterized as follows:

Yield, wt. percent of olefin	157.6
Olefin content, wt. percent	0.06
20 Organic fluorine, wt. percent	0.0008
Composition, vol. percent:	
$<C_8$ (<95° C.)	10.3
C_8 (95-125° C.)	85.3
$>C_8$ (>125° C.)	4.4

25 An aviation-gasoline cut is obtained from this alkylate in a yield of practically 100.00 per cent by volume and has an ASTM octane number of 92.8.

It will be evident to those skilled in the art that 30 my invention, by removing large volumes of inert diluent material from the olefinic feed, effects a substantial reduction in the size of equipment required for hydrofluoric acid alkylation, or a substantial increase in the capacity of existing plants. My invention makes possible the use of 35 gaseous olefinic feed material without the necessity for liquefying said material. Further, my invention makes possible the recovery, and the utilization as alkylating agent for hydrofluoric acid alkylation, of olefins present only in small proportions, such as five percent or even less, in hydrocarbon streams. Still further, my invention provides for substantially completely recovering from the olefin-depleted hydrocarbon stream hydrogen fluoride vaporized from the 40 absorbing liquid.

Obviously, there are many variations and 45 modifications of my invention, only a few of which are described herein. Additional pumps, valves, fractionators, coolers, and the like, such as are well-known in the art, may be used wherever they are desirable or convenient. It is intended that the foregoing specific examples and description of particular apparatus and operating conditions should illustrate the principles 50 of my invention and the preferred modes of practicing it, but that the scope of the invention is to be limited only by the appended claims.

I claim:

60 1. In a process for alkylating an alkylatable hydrocarbon in the presence of concentrated hydrofluoric acid, the improvement which comprises contacting in an olefin absorption step a gaseous hydrocarbon material containing olefins of three to four carbon atoms per molecule with liquid aqueous hydrofluoric acid having an acid concentration of 65 to 90 per cent to effect a dissolution of said olefins in said liquid hydrofluoric acid, said contacting also resulting in formation 65 of organic fluorine-containing compounds which are retained in the gaseous phase, separating from said contacting a liquid hydrofluoric acid phase containing dissolved olefins, contacting resulting unabsorbed gases with a relatively dilute liquid aqueous hydrofluoric acid to absorb 70 said organic fluorine compounds and vaporous 75

hydrogen fluoride, adding a resulting aqueous medium to the aforesaid liquid concentrated hydrofluoric acid, contacting unabsorbed gases with water to absorb remaining vaporous hydrogen fluoride thereby forming a weak aqueous hydrofluoric acid, discharging resulting olefin-free and hydrogen fluoride-free unabsorbed gases from the system, passing said weak hydrofluoric acid solution to a low pressure fractional distillation means and separating same into water and stronger aqueous hydrofluoric acid, passing at least a portion of said water back to the last said absorption step, passing said stronger hydrofluoric acid to a high pressure fractional distillation means, admixing with the aforesaid olefin-containing hydrofluoric acid phase sufficient more highly concentrated hydrofluoric acid to produce an acid of alkylating strength and containing more than 90 per cent of hydrogen fluoride, and contacting the same with an alkylatable hydrocarbon under alkylation conditions to effect an alkylation of said alkylatable hydrocarbon, removing from effluents of said alkylation a liquid hydrofluoric acid phase and a hydrocarbon phase, recovering from said hydrocarbon phase a fraction containing hydrocarbons resulting from said alkylation as a product of the process, passing at least a portion of the last said hydrofluoric acid phase to the aforesaid high pressure fractional distillation means, recovering from said high pressure means a substantially pure highly concentrated hydrofluoric acid and passing same to said alkylation step, and separating also from said high pressure means an aqueous hydrofluoric acid fraction and passing same to the aforesaid low pressure fractional distillation means.

2. In a process for alkylating a low-boiling isoparaffin by reaction with a normally gaseous olefin in the presence of a hydrofluoric acid alkylation catalyst, the improvement which comprises passing an olefin-containing hydrocarbon gas to a low point of an absorption zone, passing to a high point of said absorption zone as an absorption liquid aqueous hydrofluoric acid containing substantially less than 65 per cent by weight of hydrogen fluoride, passing to an intermediate point of said absorption zone concentrated liquid hydrofluoric acid in an amount such that the amount of hydrogen-fluoride in the absorption liquid initially contacting said hydrocarbon gas is between 65 and 90 per cent by weight, removing from the top of said absorption zone unabsorbed olefin-free hydrocarbon gases and from the bottom of said absorption zone a resulting rich hydrofluoric acid absorption liquid, intimately admixing in an alkylation zone said rich absorption liquid, sufficient additional hydrogen fluoride to raise the hydrogen fluoride concentration of said liquid above 90 per cent by weight, and a low-boiling isoparaffin, maintaining alkylation conditions in said alkylation zone, and recovering from effluents of said zone a hydrocarbon fraction

containing higher-boiling hydrocarbons produced by alkylation in said zone.

3. A process for removing olefins from an olefin-containing hydrocarbon gas which comprises passing a gaseous olefin-paraffin mixture to a low point of an absorption zone, passing to a high point of said absorption zone as an absorption liquid aqueous hydrofluoric acid containing substantially less than 65 per cent by weight of hydrogen fluoride, passing to an intermediate point of said absorption zone concentrated liquid hydrofluoric acid in an amount such that the amount of hydrogen fluoride in the absorption liquid initially contacting said hydrocarbon gas is between 65 and 90 per cent by weight, removing from the top of said absorption zone unabsorbed olefin-free hydrocarbon gases and washing said olefin-free hydrocarbon gases with water to remove residual hydrogen fluoride, and recovering a paraffinic gas free from olefins as a product of the process.

4. In a process for alkylating a low-boiling alkylatable hydrocarbon by reaction with a normally gaseous olefin in the presence of a hydrofluoric acid alkylation catalyst, the improvement which comprises passing an olefin-containing hydrocarbon gas to a low point of an absorption zone, passing to a high point of said absorption zone as an absorption liquid aqueous hydrofluoric acid containing substantially less than 65 per cent by weight of hydrogen fluoride, passing to an intermediate point of said absorption zone concentrated liquid hydrofluoric acid in an amount such that the amount of hydrogen fluoride in the absorption liquid initially contacting said hydrocarbon gas is between 65 and 90 per cent by weight, removing from the top of said absorption zone unabsorbed olefin-free hydrocarbon gases and from the bottom of said absorption zone a resulting rich hydrofluoric acid absorption liquid, intimately admixing in an alkylation zone said rich absorption liquid, sufficient additional hydrogen fluoride to raise the hydrogen fluoride concentration of said liquid above 90 per cent by weight, and a low-boiling alkylatable hydrocarbon, maintaining alkylation conditions in said alkylation zone, and recovering from effluents of said zone a hydrocarbon fraction containing higher-boiling hydrocarbons produced by alkylation in said zone.

5. In the process of claim 3 the additional improvement which comprises passing a resulting highly aqueous liquid hydrofluoric acid from the last said washing step to a distillation step and separating same into an acid-free water fraction and a more highly concentrated aqueous hydrofluoric acid fraction containing substantially less than 65 per cent by weight of hydrogen fluoride, returning said acid-free water to the last said washing step, and passing said more highly concentrated aqueous acid to a high point of said absorption zone.

FREDERICK E. FREY.
